(57) **CLAIM**

The ornamental design for an assembly of bioreactor components, as shown and described.

DESCRIPTION

FIG. 1 is a top perspective view of the assembly of bioreactor components showing my new design exploded for clarity;

FIG. 2 is a bottom perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof;

FIG. 8 is a bottom plan view thereof;

FIG. 9 is a top perspective view, shown assembled for clarity of disclosure;

FIG. 10 is a bottom perspective view thereof;

FIG. 11 is a front elevation view thereof;

FIG. 12 is a rear elevation view thereof;

FIG. 13 is a left elevation view thereof;

FIG. 14 is a right elevation view thereof;

FIG. 15 is a top plan view thereof; and,

FIG. 16 is a bottom plan view thereof.
